UNITED STATES PATENT OFFICE

LEWIS FERRY MOODY, OF PHILADELPHIA, PENNSYLVANIA

HYDRAULIC-POWER PLANT

Original application filed May 26, 1920, Serial No. 384,402, and in Canada August 12, 1920. Divided and this application filed May 27, 1926. Serial No. 111,951.

This invention relates to hydraulic power plants and particularly to hydraulic turbine installations in connection with dams, for instance where the power house is built as a part of the dam.

The object of the invention is to provide a hydraulic turbine installation which will be strong and compact and efficient in the handling of the flow and adapted to form part of a dam and particularly of a dam subjected to abnormal high water or flood conditions requiring an overflow of the excess water past the power station.

In many power plants, particularly for low and medium heads, it becomes a serious problem to handle these abnormal flood conditions, for in addition to providing for the passage of the water which is to be utilized in the turbines there must be additional discharge means capable of handling in the majority of developments quantities of water greatly in excess of the quantity normally flowing in the stream and far beyond the discharge capacity of the turbine passages. The usual method of disposing of the excess water is the provision of long spillway sections in the dam over which the water can pass. In power developments in which the power house is built as a part of the dam, it often becomes difficult to provide a length of dam sufficient to furnish the necessary length of spillway in addition to the space required for the power house and in such cases it is particularly desirable to carry overflow or spillway passages through the portion of the dam occupied by the power house itself.

In the accompanying drawings illustrating specific embodiments of the invention

Fig. 1 is a vertical sectional view of a turbine installation taken in a direction at right angles to the general direction of the dam.

Fig. 2 is a horizontal section of Fig. 1 on line 2, 2.

Fig. 3 is a horizontal section of Fig. 1 on line 3, 3.

Fig. 3^a is a partial horizontal section on line 3^a—3^a of Fig. 1.

Fig. 4 is a view similar to Fig. 1 illustrating a modified installation.

Fig. 5 is a horizontal sectional view on line 5, 5 of Fig. 4.

Fig. 6 is a vertical sectional elevation of a still further modification taken on a section adjacent to and following the line a b c of Fig. 7, and

Fig. 7 is a section on line 7, 7 of Fig. 6.

In the specific embodiment of the invention shown in Figs. 1, 2 and 3 a dam D has a crest C between the head water H and the tail water L and the head water face of the dam is extended backward by piers P between which are the flumes or passages 13 to the turbines and the spillway. The head gates M, sliding in ways 14 of the piers P and seating against the floor 15 of the intake, control the flow to these passages 13. Auxiliary spillway gates S are provided above the dam crest C. The flow from the head water H passes through passage 13 to the intake passage I and around to and through the turbine runner R and out through the draft tube F opening into the outlet passage O discharging into the tail-water L below the tail water level. The runner R has its shaft 20 extending upward through the crest of the dam and through the spillway passage A thereabove to drive the generator G on the power house floor or generator deck supported for instance by bridge or arch 21. Around the shaft 20 is the cylindrical pit T extending downward from the crest C and having a cover plate 22 at the crest level and a wall 23. The bottom of the pit wall 23 is provided with a conical portion 24 resting on speed ring 25 supporting the turbine head cover 28 and in turn supported upon the ledge surrounding the draft tube F. In the upper portion of the pit T braces 26 support a shaft bearing 27 and similarly the turbine head cover 28 in the bottom of the pit not only supports a shaft bearing 29 but also prevents water entering the pit thereby making the latter suitable for housing the operating means for the adjustable guide vanes 30 in the intake passage, these operating means, as shown in both Figs. 1 and 2, comprising the control ring 31 connected by usual links 31^a to turn the stems 30^a of the guide vanes and moved by fluid pressure in cylinders 32 con-

nected by piping to be controlled by a governor preferably on the power house floor above.

The walls of the pit T comprise the cast iron conical section 24 bolted to the speed ring 25 and provided at its top with the plate steel barrel 23 from this point up to just below the intermediate bearing 27 where a second cast iron section 23' is set in the concrete structure of the dam. A tube 35 extends upward from the pit cover plate 22 and around and protecting the shaft 20 from the flow in spillway A. This tube also provides a convenient passage way for access to the pit T so that the bearings and operating parts therein may be easily inspected and kept in adjustment and repair. Whenever it should be necessary to remove the working parts of the turbine the cover plate 22 would be removed from above together with the tube 35 surrounding the shaft, the generator G having first been removed. In the embodiment shown in Fig. 1 this could be done by closing the spillway gate S either with or without closing the head gates M. Whenever the local conditions should so require the spillway gate S could be arranged on the downstream side of the turbine pit T that is at or slightly beyond the downstream end of the crest C of the spillway A in which case it would be necessary to close the head gates M whenever any parts of the turbine are to be removed.

In the structure of this invention a spillway section A of the dam D is provided within the length of the power house and at the same time provision is made for removing the working parts of the turbine vertically into the power house so that these parts may be handled by the power house crane. When the open air type of generator is adopted the turbine parts can be handled by the gantry crane which would be supplied to run the length of the generator deck, the same crane being used to handle both the generators and turbines. In regular operation and when the head water level overtops the spillway crest C the excess water will pass out through the spillway A over the cover plate 22 of the pit T.

The arrangement of this invention places the various parts of the turbine installation advantageously and compactly. The generator deck is above water level giving clear access to the generators at all heads and providing plenty of surrounding space which would not be the case if the generators were sunken below the spillway level. Immediately below the generators is the spillway passage A clear but for the single tube 35 extending upwardly through it. Below the spillway crest is the pit T surrounding the shaft 20 and providing easy access to all the turbine parts at the bottom of this pit where the turbine with its operating means is compactly assembled. The water inlet I to the

turbine surrounds the pit wall 23 and utilizes the outer wall surface as its inner surface so that all the elements of the turbine fit compactly together. Similarly the draft tube F at its lower end is surrounded by the outflow passage O leading the discharge to the tail water L.

In Fig. 1 the intake I consists of the spiral inlet 45 through which the water approaches the turbine axis in a spiral curve and then is gradually turned in a helical path at 46 so that it proceeds toward the turbine with a motion compounded of rotation about the turbine axis and a vertical downward motion. The top 47 of the intake I is formed to approximate a helicoidal surface or screw thread terminating after a rotation of 360° in an edge 48 just above the turbine proper. The lower surface 49 of the intake curves gradually from the horizontal floor 15 of the gate chamber down to the edge 48, and by this design the sudden bend or elbow around which the water would have to flow in turning from the horizontal to the vertical direction, if no spiral guide walls were used, is avoided. It will be seen from Fig. 1 that if the water should turn from the horizontal to the vertical in planes parallel to that of the figure without rotating about the turbine axis, this right angle bend would cause a loss of head and a disturbed condition of the water entering the turbine. The curvature would necessarily be in most cases unduly abrupt, as shown by the small radius of the lower wall, marked 15', Fig. 1. By carrying the water in a spiral, the curvature in the direction of flow is made much more gradual. Moreover, if the water were allowed to enter the vertical portion of the conduit horizontally, it would have to pass around both sides of a circular turbine pit and then turn into the downward direction, and there would almost inevitably be eddies and surging produced at the downstream side of the circular pit. The downward flowing water would subsequently be required to assume a rotation either during its passage through the turbine speed ring or before reaching this point. If the water is turned from horizontal to vertical without conducting it in a spiral course, the flow lines would be practically indeterminate, and uncertain flow conditions would result. In the turbine casing of this invention the velocity can be closely calculated at all points of the flow between the intake and the entrance to the turbine.

The useful water flow for the turbine after passing through the speed ring 25 and adjustable guide vanes 30 enters between the blades of runner R and is discharged axially therefrom. In turbines of high specific speed such as would more usually be employed in such developments involving low heads, this axial outflow will also have a considerable

whirling motion or rotation of the discharge stream as a whole around the turbine axis. The discharge is received by the spreading draft F comprising an upper substantially straight portion of increasing cross section and a lower portion flaring outward therefrom and expanding radially with continuing increase in cross section so that the flow is turned symmetrically and smoothly into the horizontal direction and has a large part of both its axial and whirling components converted into pressure head at the entrance to the horizontal outflow O which continues to gradually increase in cross section to effect the final conversion of discharge velocity into pressure head at the tailwater L. The outflow passage O surrounds the discharge edge of the draft tube by a pair of oppositely directed half spiral collector passages 60 and 61 which extend upward as shown in dotted lines in Fig. 1 around the suspended conical draft tube walls 62 and 63 on each side, the discharge side of this draft tube wall being extended as a central pier 65 for providing a continuous foundation for the structure above.

The use of the spreading type of draft tube also offers important advantages when used with the arrangement of turbine here described, since it would be objectionable to use the older type of draft tube involving an elbow or bent passage, since the elbow type of draft tube would discharge the water into the long horizontal discharge passage with too high a velocity in the water and with too much disturbance. That is, the necessity of providing a long straight horizontal discharge passage to carry the water under the spillway section of the dam makes it desirable to use the spreading type of draft tube rather than the elbow type.

The helical formation of the intake passage I provides a supporting wall wrapping around the pit wall 23 and while in specific embodiment shown in Fig. 1 this passage turns through substantially 360° it may turn through a greater or less angle and have a correspondingly smaller or larger pitch or be otherwise modified for instance as shown in Figs. 4 and 5. To reduce the angle and increase the pitch reduces somewhat the amount of concrete and form work required in the construction but at a sacrifice of smoothness of curvature at the entrance to the casing. The choice of the angle would depend upon the economic relation between cost and efficiency in each particular installation.

In the arrangement shown in Figs. 4 and 5, the design of the intake I, and casing has been slightly modified by placing the edge 148 ninety degrees from its position in Figs. 1 and 2. The edge is here placed on the center line of the turbine in the direction of flow, that is, immediately in line with the center of the intake I, so that the upper wall

147 of the casing is carried to less than a complete revolution. This reduces somewhat the amount of concrete and form work required in the construction, and while it gives shorter and not quite so gradual a curvature at the entrance to the casing, might be preferred in some installations.

In Figs. 6 and 7 a further modification is shown, having its intake passage in two half-spirals 70 and 71 developing in opposite directions from edge 54 of the crest C, the edge 78 here being placed in line with the center of the intake but on the downstream side of the turbine pit T. This arrangement is more economical in amount of concrete required, and in some instances would probably furnish as much guidance and as smooth lines of flow as it would pay to adopt. The curvature from horizontal to vertical at the entrance is here more abrupt than in Figs. 1 to 5, but the formation of eddies behind the pit wall is prevented, and definite lines of flow are provided at all points. In this arrangement, however, the water will approach the entrance to the turbine proper without whirl, and this whirl will be introduced by the speed ring vanes 25 and 30. Fig. 7 shows in section the form of the tube 35 surrounding the shaft, which would be the same in the arrangements of Figs. 1 to 5.

The arrangement of Figs. 1 to 7 is particularly adaptable for dams under high head between the portion of the dam on the upstream side of the turbine and the overfall section downstream from the turbines, since in addition to the thickness of concrete between the turbine casings, the intermediate piers provide added connection.

(This application is a division of my co-pending application No. 384,402, filed May 26, 1920.)

I claim:

1. In a hydraulic turbine installation the combination with an inflow passage, of a turbine runner at the lowermost portion of said passage, a turbine head cover, means forming a pit above said head cover and through which said runner may be removed, said head cover substantially preventing entrance of water to said pit, a cover plate over said pit, a spillway above said cover plate, and gate operating mechanism in said pit.

2. In a hydraulic turbine installation the combination with a turbine runner having a head cover, of means forming a pit above said head cover and through which said runner may be removed, an inflow passage surrounding said pit, a cover plate over said pit, a spillway above said cover plate, and means for controlling the flow through said spillway.

3. In a hydraulic turbine installation the combination with a turbine runner having a head cover, of means forming a pit above said head cover and through which said run-

ner may be removed, an inflow passage surrounding said pit, a cover plate over said pit, a spillway above said cover plate, and means driven by said runner above the level 5 of said spillway.

4. In a hydraulic turbine installation the combination with a turbine runner, of means permitting a head water supply therefor, a turbine head cover above said runner, and 10 means forming a pit including a wall having a generally cylindrical outer surface above said turbine head cover and containing the shaft and operating mechanism of the turbine, said pit wall being adapted to be rounded by and in contact with head water. 15

5. In a hydraulic turbine installation the combination with a turbine runner, of means permitting a head water supply therefor, a turbine head cover above said runner, and 20 means forming a pit including a wall above said head cover, said pit containing the shaft and operating mechanism for the turbine, whereby head water may pass around and along said pit wall on the way to said runner. 25

6. In a hydraulic turbine installation the combination with a turbine runner, of means permitting a head water supply therefor, a turbine head cover above said runner, and 30 means forming a pit including a wall above said head cover, said pit containing the shaft and operating mechanism for the turbine, and means forming a passage whereby head water is directed around and along said pit wall 35 on the way to said runner, the walls of said passage being so formed that the water approaches the turbine runner with a relatively large vertical component of flow.

7. In a hydraulic turbine installation the 40 combination with a downwardly discharging runner, of means forming a pit above said runner, and an intake passage to said runner extending around said pit.

8. In a hydraulic turbine installation the 45 combination with a turbine runner of means permitting a head water supply therefor, a turbine head cover above said runner, means forming a pit including a wall having a generally cylindrical outer surface above said 50 head cover, said pit containing the shaft and operating mechanism of the turbine, and means whereby head water may pass around the wall of said pit along spiral helical lines.

9. In a hydraulic turbine installation the 55 combination with a runner, of a pit above said runner, means forming an intake passage to said runner extending around said pit, and means forming a spillway above said pit.

10. In a hydraulic turbine installation the 60 combination with a turbine runner, of means permitting a head water supply therefor, a turbine head cover above said runner, means forming a pit including a wall having a generally cylindrical outer surface above said 65

head cover, said pit containing the shaft and operating mechanism of the turbine, means whereby head water may pass around the wall of said pit along spiral helical lines, and means forming a spillway above said pit. 70

11. In a hydraulic turbine installation the combination with a turbine runner discharging downwardly, of means forming a pit thereabove including a generally cylindrical pit wall, and a turbine intake passage 75 surrounding said pit wall and having its inner surfaces formed thereby.

12. In a hydraulic turbine installation the combination with a turbine runner, of means forming a pit thereabove including a generally cylindrical pit wall, and a spiral helical turbine intake passage surrounding said pit wall, and having its inner surfaces formed thereby. 80

13. In a hydraulic turbine installation the combination with a turbine runner, of means forming a pit thereabove and extending upwardly to provide for the removal of said runner, means forming an intake passage located around said pit whereby fluid flows to said runner in an axially progressing direction along the walls of said pit, and means forming a discharge passage comprising a spreading draft tube and a horizontal outlet therefrom whereby the flow through 90 said intake passage and draft tube maintain hydraulic symmetry about the turbine axis. 95

14. In a hydraulic turbine installation the combination with a turbine runner, of means forming a pit thereabove and extending upwardly to provide for the removal of said runner, means forming an intake passage located around said pit whereby fluid flows to said runner in an axially progressing direction along the walls of said pit, and means forming a discharge passage comprising a spreading draft tube and an outlet surrounding the end of said draft tube and extending horizontally therefrom whereby the flow through said intake passage and draft tube maintains hydraulic symmetry about the 100 turbine axis, thereby to minimize flow disturbances. 105

15. In a hydraulic turbine installation the combination with a dam wall, of means forming a circular pit therein, a turbine having adjustable guide vanes and operating means therefor at the bottom of said pit, said operating means comprising a controlling ring linked to said guide vanes, and fluid operated means for moving said controlling rings, all of said operating means being contained within the circular walls of said pit whereby a relatively smooth external flow guiding surface is had. 115

16. In a hydraulic turbine the combination with a turbine runner, of movable guide vanes therefor, levers for adjusting said guide vanes, means forming a circular pit, and controlling means within said pit com- 120 125 130

prising a movable ring linked to said guide vane levers and operating cylinders entirely within said pit and extending above said vane levers.

5 17. In a hydraulic turbine installation the combination with a turbine runner, of means forming a pit thereabove and extending upwardly to provide for the removal of said runner, means forming an intake passage 10 located around said pit, and means forming a discharge passage comprising a spreading draft tube and a horizontal outlet therefrom and including a pier supported on the floor of said horizontal outlet whereby the super- 15 structure comprising the means forming said intake passage around said pit is supported from the floor of said outlet.

18. In a hydraulic turbine installation a structure containing a series of turbines each 20 having a downwardly discharging runner, means forming a pit above said runner, an intake passage to said runner extending around said pit, and a draft tube and discharge passage below said runner, said intake 25 passages, draft tubes and discharge passages for successive turbines being so disposed as to provide continuous supporting piers between them extending from the base to the top of the structure.
